(57) **CLAIM**

The ornamental design for a female doll, as shown and described.

DESCRIPTION

FIG. 1 is a front view of a female doll showing my new design;

FIG. 2 is a rear view of the female doll;

FIG. 3 is a left side view of the female doll, a right side view being a mirror image thereof;

FIG. 4 is a top view of the female doll; and,

FIG. 5 is a bottom view of the female doll.

The showing of dot dash broken lines is included for the purpose of illustrating environmental structure and forms no part of the claimed design. The evenly broken line depicts portions of the article that form no part of the claimed design.

1 Claim, 4 Drawing Sheets
